UNITED STATES PATENT OFFICE.

JACOB BREMS AND WILLIAM BREMS, OF CINCINNATI, OHIO.

SHOE SHANK.

Application filed March 14, 1928. Serial No. 261,451.

This invention relates to improvements in shanks or arch supports for shoes either as an insert to be applied into the finished shoe or built within the shoe.

5 Primarily, the invention is directed to a shank composed of superposed longitudinal strips constituting a pliable strip and a plurality of elastic strips rigidly connected together at the rear or heel end with the elastic strips having a loose or sliding connection with the forward end of the pliable strip to accommodate for relative variable yield of the strips under transverse pressure applied upon the shank in sustaining the

10 arch of the foot.

An object of the invention, therefore, is to provide a spring shank for shoes composed of a plurality of metal strips in superposed arrangement, and of relatively variable elasticity or resiliency, fixed together as a unit at one end and loose at the opposite end.

Another object of the invention is to provide a spring shank for shoes composed of a 25 plurality of spring metal strips secured together at the rear or heel end, loose and relatively overlapped at the forward end to form a tapering or feathered end longitudinally and avoid abruptness which might 30 cause injury to the foot.

Another object is to provide a spring shank of the nature described, adjustably attached to a half insole or covering so that when, as a permanent component of a shoe, 35 the shank is suitably anchored to an outsole, the covering or half insole may be adjusted longitudinally of the shank or shoe during assembly to suitably position the covering or half insole in relation to the outsole.

40 Other objects and certain advantages will be more fully set forth in a description of the accompanying drawings, forming a part of this specification, in which:

Figure 1 is a top plan view of the invention, illustrating it as an article of commerce adapted to be inserted in a finished shoe as an arch support.

Figure 2 is a sectional view taken on line 2—2, Figure 1, detailing the fabrication of 50 the arch support.

Figure 3 is a side elevation of the arch support.

Figure 4 is a bottom view illustrating the 55 arrangement of the various metallic elements of the arch support in relation to the half insole or covering.

Figure 5 is a perspective view of the arch support.

Figure 6 is a top plan view of a full dimension shoe sole, illustrating the invention 60 as adjustably applied thereto with the metallic base element of the arch support having its forward end socketed into a pocket in the sole, this view being illustrative of the sole and arch support during the process of 65 shoe assembly.

Figure 7 is a side elevation of Figure 6.

Figure 8 is a sectional view taken on line 8—8, Figure 6, detailing the manner of securing the metallic elements of the arch support to the sole and illustrating the means whereby the half insole or covering is adjustable in relation to the remainder of the arch support.

Figures 1 to 5 inclusive, of the drawings, 75 illustrate the improvement as an article of commerce to be inserted in a finished shoe as an arch support, while in Figures 6 to 8 inclusive, the shank is built in as a permanent component of the shoe, although in 80 either capacity they are of duplicate construction except in so far as the shape and outline of the half insole or covering to which the metallic shank members thereof are fixed, is concerned.

In the one instance, the forward end of the metallic shank members are socketed into the forward end of the half insole, while in the second instance, the metallic members are engaged into the pocket formed into 90 the inner sole of the shoe or upper side of the outer sole. Therefore, in some types of shoe manufacture, the half insole may be omitted, particularly in shoes having an inner sole as, for instance, welts, wherein the 95 shank can be inserted between the inner and outer soles so that the use of the half insole is eliminated.

As an article of commerce for an arch support or in case the shank is utilized for 100 turn shoes the metallic shank members are applied or fixed to the underside of a half insole 1, preferably of leather material. The half insole is skived at its underside along its marginal edges, forward from the heel portion, and at the forward portion to give 105 the same tapering edges allowing it to be fitted and seated snugly within the shoe. The half insole is of suitable pattern outline to correspond approximately to the 110 style and size of the inside of the shoe into which it is to be inserted.

A shank plate 2 of pliable material, as sheet aluminum, and of an appropriate pattern outline is disposed against the underside of the half insole or cover layer 1, and 5 appropriately arched longitudinally to a determined degree for a required or desired arch curvature or rise required for the user. The shank being of composite structure, the plate 2 forms a base member or leaf thereof, 10 shaped to possess the normal shank curvature when free from weight or pressure of the foot. The plate being of a bendable material is readily shaped or pressed to form, and can be conveniently die cut to 15 various pattern outlines for various orthopedic requirements. For instance, the base member can be provided with a lateral extension 3 curved laterally to provide an instep supporting lip. Padding indicated at 20 3^a may be inserted between the base member and the half insole to build up the insole to any required curvature. A plurality of flat springs 4 and 5 of relatively different rectangular cross section and length are supported or fixed at their rear ends to the base member preferably by a rivet 6 passing through the springs and base member, and the rivet may also join the half insole to the 25 metallic members.

30 The number of flat springs employed is optional and depends largely upon the capacity or load to be sustained or elasticity required. The forward end of each spring has a tongue extension 8 respectively engaged through a slot or aperture 9 in the base member and lapped upon the upperside thereof, confining each spring against lateral displacement or swing, and slidingly connecting its forward end with the base 35 member which also serves as a guard for the free ends of the springs.

The use of flat springs of different width effects an offset or tapering cross section to the underside of the structure, adapting the 45 same to be more easily fitted into the shoe and also stabilizes the structure when under stress so as not to possess any tilting tendency, nor produce a ridge which may offer discomfort to the foot when the shank is 50 under stress.

The forward end of the shank, when the product represents an article of commerce of an insert arch support, is engaged or socketed into a pocket 10 cut into the underside of the half insole or into a pocket in the inner or outer sole when the shank is inserted in the shoe at the time of making the shoe. This prevents the shank from slipping sidewise and also protects and guards 55 the free forward end of the base member, and produces a metatarsal button. Interlocking the forward end with the shoe sole or half inner sole will not cause any friction against the foot under the yielding or 60 sliding movement of the base plate.

The springs are applied to the base member in a flat condition by flexing to the curvature of the base member at the time of application and, therefore, maintain a normal shank curvature with a determined degree of stability, which may be varied or regulated by the number of springs employed, the springs being free to yield with the heavy pressure of the foot and weight of the person. 75

Referring to Figures 6 and 8 inclusive, of the drawings, as previously mentioned, the forward end of the shank is socketed into a pocket 10 formed in the sole 11 of the shoe, in this instance in the upper face of an outsole of the turn type. The half insole 1, or covering if an insole of full dimension is used, is adjustably mounted in relation to the metallic elements of the arch support by means of rivets 12 holding the arch support 80 in assembly extending through slots 13 formed longitudinally in the half insole or covering. As shown in Figure 8, the metallic elements are held together at their rear end by means of a rivet 14 corresponding to the rivet 6 of the insert type of construction and are provided with the same tongue and slot connection at their forward ends. The rivets securing the metallic element unit to the half insole, in the case of the rear one, 95 extends merely through the base element and is split and turned over, and in the case of the forward one extends through a slot in one of the spring elements 5 and through the base element being split and turned on 100 the underside of the base element.

After the covering or half insole has been adjusted to align its rear edge with the rear edge of the outsole, the rivets are smashed or spread to permanently set and secure the 105 half insole to the shank elements. This construction provides an arch support of the same nature as the insert type with the exception of the adjustability of the half insole or covering in relation to the metallic 110 elements of the arch support.

Having described our invention, we claim:

1. A shoe shank, comprising, a plate of bendable material shaped longitudinally to a determined arch curvature, and a plurality of flat springs extending longitudinally of the plate in superposed arrangement and fixed together and to the plate at the heel end thereof, each spring at its forward end slidingly connected to the plate, engaging 115 through an aperture in the plate.

2. In a shoe, a shank, comprising, a plate of bendable material and of curved formation longitudinally, and flat springs at the underside of said plate, fixed to the plate at 120 one end, with the opposite end slidingly engaged with the plate, and the forward end of said plate engaged with a pocket of a component of the shoe.

3. An arch support for shoes, comprising, 125

- a half insole, a plate of bendable material shaped longitudinally to a determined arch curvature, and a plurality of flat springs extending longitudinally of the plate in 30
5 superposed arrangement, said half insole, plate and springs fixed together at one end and each spring at its forward end slidably connected to the plate, engaging through an aperture in the plate.
- 10 4. A shoe construction, comprising, a covering of half sole dimension, a plate of bendable material shaped longitudinally to a determined arch curvature, and a plurality of flat springs extending longitudinally of 35
15 the plate in superposed relation, said plates and springs fixed together at one end and each spring at its forward end slidably connected to the plate engaging through an aperture in the plate, said covering longitudinally adjustably secured to the plate, said plate anchored to the sole of the shoe, whereby the covering may be adjusted to fit the 40
20 outline of the sole.
5. In a shoe, an arch support, comprising, 25 metallic shank elements secured together in superposed relation, flexible and slidable in relation to each other under transverse load, said elements adapted to be anchored to the shoe sole, and a covering of half sole dimension adjustably secured to the shank elements, said covering adjustable for aligning the rear edge thereof with the heel outline of the shoe.
6. A unit for a shoe, comprising, a shoe sole of full dimension, a fabricated metallic arch support anchored to the sole in longitudinal position and a covering of rear half sole configuration adjustably secured over the shank for longitudinal adjustment thereon whereby the covering edge may be 45 aligned with the shoe sole edge.
7. A unit for a shoe, comprising, a shoe sole of full dimension and a flexible metallic shank anchored to the sole in longitudinal position, a covering of rear half sole configuration, rivets secured to said shank and traversing longitudinal slots formed in said covering, said rivets initially loosely traversing the slots whereby the covering may be shifted in relation to the shank and the 50 sole, to properly position the same in relation to the sole and whereupon the covering may be permanently set by smashing the rivets.
- In witness whereof, we hereunto subscribe 55 our names.

JACOB BREMS.

WILLIAM BREMS.
